UNITED STATES PATENT OFFICE.

FRANK DUDEK, OF OMAHA, NEBRASKA.

TICKET HOLDER AND DISPENSER.

Application filed August 9, 1921. Serial No. 490,989.

To all whom it may concern:

Be it known that I, FRANK DUDEK, a citizen of the United States, residing at Omaha, in the county of Douglas and State of Nebraska, have invented new and useful Improvements in Ticket Holders and Dispensers, of which the following is a specification.

This invention relates to ticket holders and dispensers and an object of the invention is to provide a device whereby a ticket may be dispensed from a pack, one at a time, and also wherein the tickets are so arranged as to prevent spreading and disorderly arrangement of the tickets in a pack, the said 15 improved ticket holder maintaining the tickets in a compact form at all times.

Another object of this invention is to provide a ticket holder as specified which is constructed so as to permit the ready replacing 20 of a pack of tickets when necessary.

More specifically the invention comprehends the provision of a ticket holder which includes spring compressed means for maintaining the tickets in the holder, the said means being releasable to permit replacing of a used pack of tickets and one which further comprises dispensing means embodying needles which engage in the topmost ticket 30 of the pack and lifts it to permit the operator of the device to remove one ticket at a time.

Other objects of the invention will appear in the following detailed description and in 35 the accompanying drawing wherein:

Fig. 1 is a top plan of the improved ticket holder.

Fig. 2 is a side elevation of the ticket holder.

Fig. 3 is a longitudinal section through the ticket holder, taken on the line 3-3 of Fig. 1.

Fig. 4 is a cross section through the ticket holder taken on the line 4-4 of Fig. 1.

Fig. 5 is a cross section through the ticket holder taken on the line 5-5 of Fig. 1.

Referring more particularly to the drawing, the improved ticket holder comprises a main body 1 which is constructed of any 50 suitable material and is substantially rectangular in shape, providing a base 2 and upstanding sides 3 and end 4. The end 4 is provided with a cutout portion 5 to permit the user of the device to engage a ticket from 55 the pack 6 of tickets which is supported

within the body 1 upon the base 2 thereof. The base 2 is provided with an arcuate recess 7 in its end remote from the recessed end 4 of the body and a pressure member 8 is pivotally connected to the body 1 as shown 60 at 9 outwardly of the depressed portion 7. The pressure member 8 curves over the depression 7 and has depending ears 10 formed thereon to which is connected a pressure rod or bolt 11 which engages the pack 6 of tickets and forces one end of the same downwardly into the depression 7. The pressure member 8 has a forwardly extending upwardly curving ear 12 formed thereon in which a pin 13 rests. A spiral spring 14 is 70 coiled about a spring carrying bolt 15 and is bent intermediate its ends to provide spaced lengths 16 which are held in proper spaced relation by the spacing sleeve or collar 17. The spaced lengths 16 are coiled about the 75 ends of the pin 13 and held against movement off the ends of the pin by transverse pins 19. The lengths 16 of the spring extend upwardly from the pin 13 providing a handle 20 to permit the removal of the 80 pin 13 from the depression in the ear 17 and consequently to release the pressure on the pressure member 8 and allow it to be swung outwardly on its pivot 9 to release the pack 6 of tickets when necessary or desired. 85

A dispensing structure 21 is carried by the body 1 and it comprises a carrying rod 22, one end of which is connected as shown at 23 to ears 24 formed upon one of the sides 3 of the body and it moves through a recess 90 25 in the body to permit proper insertion of the bolt 23 through the ears 24 and end of the rod. A sleeve 26 is rotatably mounted upon the rod 22 and is held against longitudinal movement thereon by a suitable pin 95 27. The sleeve 26 has longitudinally spaced needle carrying bosses 28 formed thereon which carry needles 29 and it has a stop plug 30 formed thereon intermediate its ends and extending into the opposite direction 100 from the needles 29 for limiting the rocking movement of the sleeve in the direction to raise the needles. An operating thumb rest 31 is also formed upon the sleeve 26.

In dispensing tickets by means of the improved ticket holder and dispenser, the weight of the needles 29 and their carrying bosses 28 will cause the needles to engage the topmost ticket in the pack 6 and when it is desired to dispense a ticket the sleeve 26 110

is rocked by movement of the operating thumb rest 31 towards the pressure member 8 which will raise the needles 29 and as these needles have sharp points they will engage 5 in the topmost ticket and lift it upwardly and permit the operator to engage the raised ticket by placing his thumb and finger in the cutout portions 5 and 6 he can easily tear the ticket from the pack 6. After the ticket 10 has been removed the sleeve 26 is released and it will fall, by gravity, to its normal position with the needles 29 again engaging the topmost ticket in the pack.

It is to be understood that the tickets may 15 be carried by the stub end in the usual or approved manner which stub end is engaged by the pressure rod 11 to securely hold the pack in the dispenser. When it is desired to replace a pack of tickets the pin 13 is removed 20 out of the depression in the ear 12 which relieves the pressure member 8 of the spring pressure and the member 8 may be then rocked or moved outwardly on its pivot 9 to permit replacing of a pack of tickets. 25 A finger knob 36 may be carried by the pressure member 8 if desired to facilitate its movement. After the pack of tickets has been properly placed in the body 1 the member 8 is again moved to its normal position 30 and the pin 13 snapped back into the depression in the ear 12 which will cause the spring 14 to act upon the pressure member 8 and rod 11.

It is of course, to be understood that the 35 invention may be constructed in various other manners and the parts associated in different relations and therefore, I do not desire to be limited in any manner except as set forth in the claims hereunto appended.

Having thus described my invention what I claim is:

1. In a ticket holder and dispenser, a body 40 provided with a ticket supporting base, a pressure member pivotally carried by said body, a ticket pack engaging pressure rod carried by said member, and tensioning

means engaging said member for urging said rod in engagement with a pack of tickets.

2. In a ticket holder and dispenser, a body 45 provided with a ticket supporting base, a pressure member pivotally carried by said body, a ticket pack engaging pressure rod carried by said member, tensioning means 50 engaging said member for urging said rod in engagement with a pack of tickets, a rockable sleeve, a needle carried by said sleeve and adapted to engage a ticket and lift the ticket upon movement of the sleeve in one direction.

3. In a ticket holder and dispenser, a body 55 provided with a ticket supporting base having a depression in one end, a pressure member pivotally carried by said body adjacent said depression, a ticket pack engaging pressure rod carried by said member, tensioning 60 means removably engaging said member for urging said rod in engagement with a pack of tickets, a rockable sleeve, a needle carried by said sleeve and adapted to engage a ticket and lift it upon movement of the rod in one 65 direction.

4. In a ticket holder and dispenser, a body 70 provided with a ticket supporting base having a depression in one end, a pressure member pivotally carried by said body adjacent 75 said depression, a ticket pack engaging pressure rod carried by said member, and tensioning means removably engaging said member for urging said rod in engagement with a pack of tickets.

5. In a ticket holder and dispenser, a body 80 provided with a ticket supporting base having a depression in one end, a pressure member pivotally carried by said body adjacent said depression, a ticket pack engaging 85 pressure rod carried by said member, an ear formed upon said member, a pin engaging said ear and a tensioned spring connected to said pin for forcing said first named rod in engagement with a pack of tickets.

In testimony whereof I affix my signature.

FRANK DUDEK.
